UNITED STATES PATENT OFFICE.

WILLIAM CHARLES CARR, OF BUFFALO, NEW YORK.

SWITCH-BOX FOR ELECTRIC TRUCKS.

1,139,954.

Specification of Letters Patent. Patented May 18, 1915.

Application filed April 16, 1913. Serial No. 761,453.

To all whom it may concern:

Be it known that I, WILLIAM C. CARR, a citizen of the United States, residing at Buffalo, in the county of Erie and State of New York, have invented certain new and useful Improvements in Switch-Boxes for Electric Trucks, of which the following is a specification.

This invention relates to improvements in switch boxes and primarily to boxes of that class designed to be used on electric trucks or the like.

The principal object of the invention is to provide a simple, strong and compact switch structure which is inclosed and protected within a separable box or housing attached to a suitable portion of the truck or other vehicle.

This invention also relates to certain details of construction which will be hereinafter described and claimed, reference being had to the accompanying drawings, in which a preferred adaptation of the invention is shown.

Figure 1 is a top plan view of an electric truck equipped with the improved switch box with portions broken away to show the switch box in position relative with other mechanism of the truck. Fig. 2 is an enlarged top plan view of the improved switch box with the cover or top member of the box removed from the lower member to expose the construction of the switch mechanism. Fig. 3 is a vertical longitudinal section through the improved box on line A A, Fig. 2. Fig. 4 is a vertical transverse section through the improved box on the line B B, Fig. 2. Fig. 5 is a vertical transverse section through the improved box on the line C C, Fig. 2.

In referring to the drawings in detail, like numerals designate like parts in the preferred adaptation of the invention shown.

The casing or housing which constitutes the box proper of the switch mechanism consists of two members or parts, a lower or supporting member, 1, and an upper member or cover, 2 which is pivotally attached or hinged at one end to the lower supporting member 1, by means of a hinge or pivot pin, 3. The switch mechanism as shown consists of a slide 4, upon which the circuit connecting mechanism is mounted and a

supporting slide block, 5, which is rigidly fastened to the top surface of the lower member, 1 by bolts 6, as shown in Fig. 3. The slide, 4 of the switching mechanism is provided with a plurality of circuit connecting fingers, preferably two, 7 and 8, which are mounted on spring plates, 9 being fastened to said spring plates by screws, 10 and said spring plates 9, being in turn fastened to a supporting block 11. The supporting block 11 is mounted on the slide, 4 and is thoroughly insulated from said slide by a strip of insulating material or fiber 12. The block 11, together with the fiber strip 12, is fastened to the slide 4, by bolts, 13, as shown in Figs. 2 and 3. A jumper 14, of braided wire or some other suitable conducting material extends between and is fastened to the fingers 7 and 8, electrically connecting said fingers, and they allow the electric current to pass from one finger to the other. The supporting block 11, has a lateral extension, 15, which is longitudinally hollowed or grooved out on its under side as shown at 16, in Fig. 3 and a lock spring, 17, which is fastened to the top surface of a block of insulating material or fiber, 18 by screws, 19 with a bent portion 20 which is adapted to spring into the groove 16, and thus lock the slide in its circuit closing position, as shown in Fig. 3. A connecting rod 21, passes through an opening in and is supported by a boss, 22, extending from one end of the lower member 1 and the inner end of the said rod, 21, is screwed into a slotted block, 23, which is adjustably fastened to the slide by a shouldered screw, 24. The slot 25, in the block 23, extends lengthwise of said block and said block is provided at one end with a vertical projection, 26, having an upper opening, 27, through which one end of a spring, 28, is fitted as shown in Fig. 3. The opposite end of the spring, 28, is fastened to the head of one of the bolts, 13, by a screw, 29, as shown in Fig. 3. The spring, 28, yieldingly connects the rod, 21, to the slide and as the screw 24, is fitted loosely in the slot 25, the connecting rod is free to move independently of the slide the length of the slot against the tension of the spring, thereby producing a spring tensioned connection between the rod and slide.

A series of fixed electric terminals, prefer-

ably three, which are separately designated by the numerals, 30, 31 and 32, extend vertically down through openings in the lower member, 1, of the casing and the insulating block, 18, being mounted on the top surface of said member and each being provided with a top T shaped head, 33, as shown in Fig. 5, and contact plates which are also preferably three in number, and designated 10 by the numerals, 34, 35 and 36, are mounted on said terminal heads, being fastened thereon by screws, 37, fitted in counter screw openings, as shown in Figs. 2 and 5. The contact plates are so located and arranged 15 that at first a low speed is cut in by the spring finger, 8, contacting with the contact plate, 34, which completes an electric circuit through a suitable resistance and thereby a friction movement of the slide finger, 8, 20 contacts with the contact plate, 35, and completes an electric circuit directly with the battery cutting out the resistance. The contact plates, 34 and 35, extend transversely of the box and contact plate, 36, extends longitudinally and at one side of the transverse contact plates, 34 and 35. The spring finger, 7, is always in contact with the longitudinal contact plate, 36, at some point on its surface when the motor is in operation as will be 25 noted by referring to Figs. 2 and 3 and thus serves to complete the electric circuit. The terminals, 30, 31 and 32 are held in position by small downwardly projecting pins, 38, which fit into corresponding holes in the insulated block, 18, as shown in Fig. 5. The terminals are thoroughly insulated from the lower member 1, by the tubular fiber bushings, 39, and fiber washers, 40, are located beneath the lower member, 1, as shown in 30 Fig. 5.

In Fig. 1 the improved switch box is shown attached in operating position to an electric storage battery truck, a portion of which is broken away to disclose the switch box. In said Fig. 1 the switch box as a whole is designated by the numeral 42, and is mounted on the frame 43, of the truck directly over the rear axle, 44. The connecting rod, 21, is connected to a rock arm, 45, 45 which is manually actuated and has a forward extension which is attached to brake, 46, on a counter shaft, 47. The counter shaft, 47, is connected by a chain, 48, to a motor which is adapted to be driven by 50 electric power derived from a storage battery and in turn is operatively connected to the driver axle of the truck. The steering axle, 49, of the truck is turned by any well known manually controlled mechanism to 55 steer the truck.

It should be understood that while the improved switch box is shown in connection with a storage battery truck, it is equally adapted to and may be used in connection

with any electrically driven vehicle. Also 65 that the parts of said improved switch box may be modified or changed or some altogether omitted within the spirit of the following claims without departing from my invention.

The switch mechanism is changed from a circuit breaking position to a circuit closing position by moving the connecting rod, 21, and with it the slide and its spring fingers from the position shown in full lines in Fig. 75 3 to the position shown in dotted lines in said Fig. 3. This brings the fingers in contact with the contact plates and completes the circuit, as shown in Fig. 3. The circuit is broken by moving the connecting rod and 80 slide in the opposite direction and thus returning it to the position shown in full lines in Fig. 3.

It will be noted that the switch mechanism is completely inclosed and protected within 85 the casing when the upper member of said casing is closed against the lower member and is quickly exposed for repair or replacement when the upper member is raised from the lower member.

I claim,

1. A switch mechanism consisting of a stationary element and a movable element and adapted to be moved into and out of circuit closing position with reference to the 95 stationary element, said movable element including a slide and connecting rod having a slotted block loosely bolted to the slide, and a spring for yieldingly tensioning said connecting rod against a pull.

2. A switch mechanism including a casing, a slide movable therein, contact fingers carried by the slide, a projection movable with the slide and extending laterally of the contact fingers, a member carried by the casing 105 to interlock with the projection, an operating rod and a spring connection between said rod and slide.

3. A switch mechanism including a casing, a slide mounted therein, spaced electric contact fingers carried by the slide, fixed contacts arranged in the path of movement of said contact fingers, said fixed contacts including a pair of contacts to be engaged by one finger and a single contact to be engaged by the other finger, the pair of contacts having the same dimension in the plane of movement of the finger as the single contact, a rod for operating the slide, and a spring yieldingly connecting said rod and slide.

4. A switch mechanism consisting of a stationary contact, a slide, a movable contact element, a spring strip forming the sole connection between said slide and movable element, a connecting rod, and a spring forming the operative connection between 125 said rod and slide.

5. A switch mechanism including a casing,

a slide mounted for movement therein, a block secured by the slide, said block having a lateral projection formed with a notch in its under surface, a spring fixed to the casting and having the terminal form to engage the notch, fixed contact elements, and movable contact elements, having spring connection with the slide for movement therewith.
